COMBINATION FLEXIBLE DISPENSING CLOSURE
CAP AND APPLICATOR

Morton B. Stull, Garfield, N. J.

Application October 21, 1957, Serial No. 48,186

Term of patent 14 years

(Cl. D58—26)

Fig. 1

Fig. 2

Fig. 3

I claim:

The ornamental design for a combination flexible dispensing closure cap and applicator, as shown.
